HASP

Filed April 18, 1927

UNITED STATES PATENT OFFICE.

HARRY L. WORTHMAN, OF SUPERIOR, WISCONSIN.

HASP.

Application filed April 18, 1927. Serial No. 184,620.

This invention relates to closures for receptacles and has special reference to novel means for securing said closure.

The particular object of the invention is to provide a simple and practical means for selective entrance to a receptacle, such, for example, as used in the housing of fire extinguishers or the like.

Other objects and advantages will appear in the further description of the invention.

Referring now to the accompanying drawing, forming part of this application, and wherein like reference characters indicate like parts:

15 Figure 1 is a front elevation of a receptacle, such as may be used for the storage of a fire extinguisher;

Figure 2 is a side elevation of Figure 1;

Figure 3 is a section on the line 3—3, Figure 1; and

Figure 4 is a similar sectional view showing the hasp as released by the breaking of the glass.

1 represents a rectangularly shaped receptacle having the hinged door 2 mounted upon the front thereof, and in which door there is an opening 3, normally closed by the insertion of the pane of glass 4, the latter being held in position by suitable Z-shaped 30 clips or stops, indicated at 5. In the edge of the opening 3, adjacent the free edge of the door is formed a notch 6, said notch being sufficiently deep to form an opening intermediate of the innermost edge thereof and the edge of the pane of glass 4, the same being for the reception of the hooked end 7 of the locking hasp which comprises the hingedly united sections 8 and 9. When the section 8 is hooked in behind the pane of

40 glass as clearly shown in Figures 1, and 3, the hinged portion of the hasp is designed to occur just opposite the corner of the receptacle, and the section 9 conveniently engages the common staple 10 into which any 45 form of padlock may be installed, as indicated at 11.

When the hasp is engaged in this manner for retaining the glass in position, it is quite evident that the same may be securely locked against pilfering, and when it becomes essential to enter the box hurriedly as in the event of fire or the like, the glass may be

readily broken for free entrance to the box by the opening of the door, as instantly upon the breaking of the glass the section 8 of the 55 hasp will be released, even though the opposite end thereof remains locked.

It is evident that while I have illustrated the device as being applicable to a fire extinguisher box, the same may be employed 60 to advantage for many other purposes in which it is desired to associate a breakable seal with the opening of a door.

Having thus described my invention, what I claim and desire to secure by Letters Patent, is:

1. The combination with a door carrying a glass panel, of a two-part hasp one part of which is designed for engagement about the glass within the panel for holding the glass 70 normally in position, and the other part to be locked for holding the door normally closed.

2. The combination with a door carrying a glass panel, of a hasp one end of which is designed to protrude through the door 75 for normally holding the glass in position but freed when the latter is broken.

3. The combination with a door carrying a breakable panel, of a hasp one end of which is designed to hold the panel in position and be sealed thereby but may be freed by breaking the panel.

4. The combination with a receptacle of the class described carrying a hinged door thereupon, said door having a glass panel 85 therein, of a foldable hasp one part of which is designed for engagement about an edge of the glass within the panel for normally holding the door in closed position, and another part of the hasp designed to be locked to the 90 receptacle.

5. The combination with a receptacle carrying a hinged door having a breakable removable panel therein, of a hasp one end of which is designed for locked engagement about an edge of the panel for normally holding the panel in position and the door closed but freed by breaking the panel, and the other end of the hasp designed to be locked to the receptacle.

In testimony whereof I affix my signature.

HARRY L. WORTHMAN.
